UNITED STATES PATENT OFFICE.

SANFORD C. BRADY, OF BARTLESVILLE, OKLAHOMA.

PUMP.

Application filed June 6, 1922. Serial No. 566,872.

To all whom it may concern:

Be it known that I, SANFORD C. BRADY, a citizen of the United States, residing at Bartlesville, in the county of Washington and State of Oklahoma, have invented new and useful Improvements in Pumps, of which the following is a specification.

My present invention has reference to a means for elevating water from a cistern, 10 stream or the like.

My object is to produce a simple, cheap and effective means in which water may be raised from a base at a continuous flow to any desired elevation.

15 A further object is to produce a means for elevating water or similar fluids in which a casing has its bottom provided with an opening whose passage is controlled by an inwardly opening valve and which is designed 20 to rest in a supply of water, such as a cistern, said casing having passing therethrough a fluid outlet pipe which is provided with a ball valve for closing the bottom thereof but which valve is designed to be opened by the 25 pressure of water from the cistern so that the water in the casing and in the pipe will be substantially level with that in the cistern, while weight influenced means is provided 30 for operating valves to permit air under pressure entering the casing to eject water through the outlet pipe therefor when a determined quantity of water has entered the 35 casing, and upon the fall of the water to close the air inlet and to open the air outlet to permit an additional supply of water from the casing and the outlet pipe, such operation being continuous as long as the water is being elevated from the cistern.

40 The foregoing, and other objects which will present themselves as the nature of the invention is better understood, may be accomplished by a construction, combination and operative association of parts such as is disclosed by the drawings which accompany 45 and which form part of this application.

In the drawings:—

Figure 1 is a general view of the improvement arranged in a cistern or other source from which water is to be elevated, the wall of the cistern being in section.

50 Figure 2 is an enlarged approximately central vertical longitudinal sectional view

through the improvement, the water therein being at its lowest level.

Figure 3 is a side elevation with parts 55 broken away.

Figure 4 is a sectional view approximately on the line 4—4 of Figure 3.

Figure 5 is an elevation with parts in section, showing the manner in which the valves 60 are adjustably secured to the sliding frame.

While my improvement is designed for use in elevating water from streams and other sources, I have, for the purpose of illustration, shown in the accompanying drawings, 65 the same arranged in an ordinary cistern, the said cistern being indicated in the said drawings by the letter C.

In carrying out my invention, I make use of a preferably cylindrical casing 1. The 70 casing 1 is open at both of its ends, but the said ends are closed by castings. The top casting indicated by the numeral 2, has its flat under face provided with an annular groove 3, in which there is preferably arranged a gasket, and in the groove 3 the upper end of the casing 1 is received. The bottom casting 4 has its upper flat face likewise provided with an annular groove 5 in which is seated a gasket. The under face of 80 the bottom casting 4 is provided with ribs or legs 6 which elevate the bottom of the casting above the bottom of the cistern 1.

Passing through suitable aligning openings in the castings which provide the top and bottom plates of the cylinder there are bolts 7, suitable nuts 8 being screwed on the bolts for forcing the ends of the casing into the grooves 3 and 5 and in tight contact with the washers in the said grooves.

85 The bottom 4 of the cylinder is centrally provided with a round opening 9, and screwed in this opening there is a seat 10 for a weighted valve 11, the valve opening inwardly of the casing.

90 Screwed in the seat 10 there is a T, and screwed in the ends of the T are pipes having couplings on their ends provided with short pipes. In this manner the water from the cistern is directed to the valve seat.

100 Screwed or otherwise secured in a central opening in the top 2 of the casing 1 there is a tubular member 12. This member terminates a suitable distance above the bottom 4

of the casing, the lower end of the said tube being provided with a valve seat 13 for an inwardly opening spherical valve 14. Also screwed in the central opening in the top 2 of the casing there is a pipe member 15. This pipe extends a suitable distance above the cistern and provides the water outlet.

The top 2 of the casing is bored from one of its edges to provide a passage or port 16, the said casting 2 being also bored right angularly with respect to the passage 16 to provide a passage or port 17 which, of course, intersects the port 16. The outer ends of these ports are also threaded for the reception of closure plugs 18 and 19 respectively. In the bore of the port 17, at the portion thereof which communicates with the casing 1 there is secured a valve seat 20 for a ball valve 21. The port 16 provides an air inlet port, and communicating with the said port 16 there is an air conducting pipe 22.

The top 2, adjacent its opposite end is provided with a straight port or passage 23 which has in its lower wall a valve seat 24 for a ball valve 25. The valves 21 and 25 are provided with stems 26 and 27 respectively. The stem 26 extends into the casing 1, the stem 27, for the valve 25 extending both in the casing 1 and through a guide in the port or passage 23. The stems 26 and 27 have their inner ends loosely received in sleeves 28. A pin 26' passes through the valve stem and slots 28 in the sleeves. The sleeves are interiorly threaded and are screwed on the parallel arms 29 of a substantially U-shaped frame. The lower or connecting member of the frame is indicated by the numeral 30. This member 30 is centrally provided with a ring flange 31 that surrounds the tube 12. The members 29 of the frame are connected by a brace 32, disposed only a slight distance from the connection of the arms 29 with the valve stems 26 and 27. The frame is preferably in the nature of a rod member, as is the brace 32; the said brace being centrally formed with a ring portion 33 that surrounds the tube 12. Arranged for free movement around the tube 12 between the bottom 30 of the frame and the brace 32 there is a float 34.

Air or other fluid under pressure is conducted through the pipe 22, and the said pipe has its passage controlled by a valve (not shown).

The arms 29 of the frame have preferably screwed thereon nuts 36 which are in contact with the sleeve members 28, so that the frame may be effectively held adjusted on the valve stems 26 and 27.

On the brace 32 there is an upwardly directed arm having an angle end or finger 36'. This finger is movable between two weighted members 37 which are pivotally supported at 38 to the under face of the casting 2.

The weighted members have their confronting faces notched at spaced intervals.

The operation may be briefly described as follows:

We will suppose that the air inlet control valve 21 is seated and the air outlet control valve 25 is unseated. Water from the cistern will flow into the casing through the opening 9, unseating the weighted valve 11, and such water will likewise enter the tube 12. The water in the casing will elevate the float 34, and when the same rises sufficiently, it will contact with the brace 32, and in so doing will raise the frame 29 to open the air inlet valve 21 and close the air outlet valve 25. Air will now enter the casing through the passages 16 and 17 and exert pressure on the water in the casing, will force such water through the pipes 12 and 15 and will also, of course, close the valve 11. The finger 36' is now engaged in the aligning notches in the pivoted weights 37 and will tend to hold the frame elevated and the valve 20 insulated until all of the water in the casing is displaced. The frame will then by its own weight, descend and cause the seating of the valve 21 and the unseating of the valve 25. The air now finds an outlet through the open valve seat 24 and the port 28, allowing the pressure of the water in the cistern to again unseat the valve 11 and enter the casing. The operation is continuous as long as water enters the casing 1, and air is likewise permitted to enter the casing.

It is thought that the foregoing description, when taken in connection with the drawings will fully set forth the construction, operation and advantages of the improvement to those skilled in the art to which this invention relates, and therefore further detailed description will not be attempted. It is thought necessary to add, however, that the description and illustration refer only to a satisfactory embodiment of the improvement as it now appears to me and that I am entitled to all such changes therefrom as fall within the scope of what I claim.

Having described the invention, I claim:—

In an apparatus as herein described, a casing designed to be arranged in a body of water having a valve controlled inlet at the bottom thereof, and a valve controlled outlet at the top thereof which projects above the level of the water, said casing having its top provided with a valve controlled inlet port for a fluid under pressure and a valve controlled outlet port for said fluid, stems for the last mentioned valves, a substantially U-shaped frame adjustably secured on the stems, a brace member between the arms of the stems, and said float being positioned between the said brace and the lower element of the frame to contact with these

members on the rise and fall of the float for influencing the frame to cause the latter to simultaneously and alternately open and close the last mentioned valves, notched 5 weights suspended from the casing, a finger on the frame movable therebetween and designed to be received in the notches there-

of when the frame is moved to one position to hold the frame and sustain the fluid inlet valve open after the float has been lowered 10 from contact with the brace, as and for the purpose set forth.

In testimony whereof I affix my signature.
SANFORD C. BRADY.
